UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

POWER-TRANSMITTING MECHANISM.

1,160,986.

Specification of Letters Patent. Patented Nov. 16, 1915.

Application filed April 12, 1915. Serial No. 20,667.

To all whom it may concern:

Be it known that I, JOHN KIEWICZ, a citizen of the United States, residing at Boston, county of Suffolk, State of Massachusetts, have invented an Improvement in Power-Transmitting Mechanism, of which the following description, in connection with the accompanying drawing, is a specification, like characters on the drawing representing like parts.

This invention relates to power-transmitting mechanism, such as is used to transmit power from a power element to a machine to be operated, and particularly to transmitting mechanism adapted to drive a machine that is constructed to be moved bodily from its operative position into an inoperative position, and the object of the invention is to provide a power-transmitting mechanism so constructed that when the driving connection between the power element and the machine is inoperative, said machine can be shifted from its operative to its inoperative position, while when the machine is in its operative position, the driving connection between the driving element and said machine can be established.

In the illustrated embodiment of my invention the driving connection between the power element and the machine to be operated is in the nature of belts and pulleys, and the construction is such that it is not necessary for the operative to disconnect the belt from the machine before shifting it from one position to the other.

While my invention is capable of use in connection with various machines that are constructed to be shifted bodily from one position to another, I have chosen herein to illustrate it as it would be used in connection with a buttonhole sewing machine of the "Reece" type, such, for instance, as is shown in United States Patents No. 488,028, December 13, 1892, No. 494,280, March 28, 1893. These sewing machines are usually pivotally mounted on a frame or base so that they can be turned about their pivot from their operative position to their inoperative position in which some parts of the stitching mechanism are exposed to view. In using these machines it is necessary for the operative to turn the machine bodily about its pivot at various intervals in order to permit him to have access to various parts of the machine that are concealed within the base when the machine is in operative position.

The driving mechanism usually employed on machines of this type is a driving belt passing around a driving pulley secured to the machine and driven from a pulley on a shaft operating about a fixed axis. In order to permit the machine to be turned from its operative to its inoperative position with the driving construction heretofore provided has necessitated the removal of the belt either from the driving pulley of the machine or from the pulley on the fixed driving shaft, and in order to start the machine up again has necessitated replacing the driving belt onto the pulley from which it has been removed.

I have provided herein a belt power-transmitting device which permits the machine to be shifted from its operative to its inoperative position without the necessity of removing any belts from their pulleys, the construction being such that when the driving belt is operating on the loose pulley and is, therefore, inoperative to drive the machine, the latter can be shifted from its operative to its inoperative position, and when said machine is in its operative position it can be started by simply shifting the belt from a loose to a fast pulley. This shifting of the belt from the fast to the loose pulley and vice versa is controlled from a treadle with which machines of this sort are usually equipped in order to start and stop them.

In order to give an understanding of my invention I have illustrated in the drawings a selected embodiment thereof which will now be described, after which the novel features will be pointed out in the appended claims.

In the drawings, Figure 1 is a side view of a sewing machine of the type above referred to having my improved power transmitter applied thereto and showing the machine in its operative position; Fig. 2 is a similar view showing the sewing machine raised into its inoperative position and the transmitting mechanism inoperative; Fig. 3 is an enlarged fragmentary view of the countershaft and loose pulley showing the countershaft both in its operative and inoperative position; Fig. 4 is a detail of the frame for supporting the countershaft; Fig. 5 is a section on the line $x-x$, Fig. 1.

I have shown at 1 a machine to be operated which for illustrative purposes is shown as a buttonhole sewing machine of the so-called "Reece" type such as described in the

above-mentioned patents. I wish to state, however, that the machine itself forms no part of the invention and that said invention can be applied to various machines.

5 The sewing machine is shown as sustained on a suitable support herein designated as comprising a bench or table 2 carrying a base frame 3 to which the sewing machine is pivotally mounted, as at 4, thus permitting 10 the sewing machine to be raised from its operative position shown in Fig. 1 to its inoperative position shown in Fig. 2.

The machine 1 is shown as provided with a driving pulley 5 by which the stitching 15 mechanism is operated, this pulley being driven from a belt 6, said belt extending down through the bench or table 2 and being driven from a shaft below the table. For convenience and identification purposes I 20 will refer to the belt 6 as the transmission belt.

If the shaft from which the transmission belt 6 is driven is mounted in fixed bearings it will be evident that in order to raise the 25 machine from its operative position shown in Fig. 1 to its inoperative position shown in Fig. 2 will require that the belt be disengaged either from the pulley 5 or from the pulley from which the belt is driven.

30 To obviate this difficulty I have provided a countershaft beneath the table 2 carrying a pulley over which the belt 6 runs, and this countershaft is sustained for vertical movement so that it will rise and fall with the 35 machine 1 when the latter is moved from one position to the other. This countershaft has a pulley fast thereon and the construction is such that when the machine is in its operative position the countershaft 40 will be properly positioned to bring the fast pulley thereon in axial alinement and closely adjacent to a loose pulley operating in the fixed bearing and over which a driving belt passes so that the driving belt can be shifted 45 from the loose to the fast pulley and thereby operate the machine. When this driving belt is running on the loose pulley, however, the countershaft with the fast pulley can be raised with the machine 1, thus obviating 50 the necessity of taking the belt 6 off from one of the pulleys over which it operates. The pulley which drives the belt 6 is shown at 7 and it is fast on a countershaft 8 which has fast thereon a pulley 9 hereinafter referred to as the fast pulley. This countershaft 8 is sustained in a suitable frame 10 secured to the table 2 for vertical movement so that as the machine is shifted from the operative position shown in Fig. 1 to its 55 inoperative position shown in Fig. 2, the countershaft 8 may rise with the machine. The fast pulley 9 receives its power when the machine is operated from a driving belt 11 which is shown as passing over a pulley 12 on a power driven shaft 13 operating in

fixed bearings. 14 is a so-called loose pulley which is loosely mounted on a stud shaft 15 carried by a suitable bearing 16 secured to the table 2.

The frame 10 is so mounted and the fast 70 pulley 9 is so positioned thereon that when it occupies the position shown in Fig. 1 and the machine 1 is in its operative position, the shaft 8 is co-axial with the shaft 15 and the loose pulley 9 is closely adjacent to the fast 75 pulley 14, as seen in Figs. 3 and 5. When the parts are in this position the driving belt 11 can be readily shifted from the loose to the fast pulley or vice versa in the same way as if the fast and loose pulleys were 80 mounted on the same shaft. The shifting of the belt 11 from the loose to the fast pulley will, of course, drive the countershaft 8 thereby driving the pulley 5, while the shifting to the loose pulley will allow the 85 machine to come to rest.

By making the frame 10 movable it will be carried into the position shown in Fig. 2 when the machine 1 is lifted into its inoperative position if the belt 11 is running on the loose pulley 14. The frame 10 is herein shown as pivotally mounted on the shaft 17 secured in the bracket 18 fastened to the table 2, and said frame has secured thereto and extending therefrom a strut member 19 which extends up through the table and base frame 3 and the upper end of which occupies a socket 20 formed on the underside of the machine 1. The frame 10 is acted upon by suitable spring mechanism which yieldingly holds the strut member 19 in its socket. This spring mechanism is herein shown as constituted by two springs 21, each of which is wound about the hub portion 22 of the frame 10 and at one end is secured to a collar 23, the other end 24 of which is extended under the yoke portion of the frame. The tendency of the springs 21, therefore, is to lift the frame and thereby keep the strut 19 in the socket 20. The collars 23 are 105 shown as loosely mounted on the shaft 17, and each collar is provided with a stop pin 25 engaging the shoulder 26 formed on the bracket 17 which holds the collar from rotation. This pin 25 can be adjusted into 110 any one of several apertures 28 formed in the collar, thereby to adjust the tension of the spring. With this construction the shifting of the machine 1 from its operative to its inoperative position and vice 115 versa results in a corresponding movement of the frame 10, and as stated above, the parts are so proportioned and constructed that when the machine is in its operative position the frame 10 will be lowered into a 120 position to bring the shaft 8 co-axial with the shaft 15, as shown in Fig. 1.

The shifting of the power belt 11 from the fast pulley 14 to the loose pulley 9 is herein provided for by means of a belt shifter 120

which is operated from a treadle 31 pivoted at 32 to a suitable bracket 33. The construction herein illustrated is such that swinging movement of the treadle in one direction, as, 5 for instance, that which will result in the pressure of the toe of the operative on the left-hand end of the treadle, Figs. 1 and 2, will operate the belt shifter 30 to shift the belt from the loose to the fast pulley, while 10 movement of the treadle in the opposite direction into the position shown in Fig. 2, which can be accomplished by a pressure of the heel of the operative on the right-hand edge of the treadle, will operate the belt shifter 30 to shift the belt from the fast to the loose pulley. Any suitable mechanism for 15 connecting the treadle to the belt shifter may be employed. As herein shown, the belt shifter 30 is carried by a sleeve 34 slidably mounted on the shaft 15, and this sleeve is pivotally connected at 35 to one arm of an elbow-lever 36 that is pivoted at 37 to the bracket 16. Said elbow lever is connected to the treadle by a link or connection 38. With 20 this construction the movements of the treadle above described will shift the power belt 11 from the loose to the fast pulley and vice versa. The belt-shifting mechanism is provided with means for yieldingly holding 25 it in either of its two positions and the construction herein illustrated for this comprises a frictional locking pin 39 slidably mounted in the boss 40 carried by the lever 36 and backed by a spring 41, said pin being 30 adapted to engage in either one of two notches 42 or 43 formed in the bracket 16. This provides a frictional lock for frictionally and yieldingly holding the lever 36 in 35 either of its two positions.

40 It will be seen from the above that when the machine 1 is in its operative position shown in Fig. 1 the power belt 11 can be shifted from the fast to the loose pulley and vice versa in exactly the same way as if the 45 fast and loose pulleys were on the same shaft and the machine can thus be controlled from the treadle, as usual in machines of this type.

When the operative wishes to raise the 50 machine 1, he will simply operate the treadle 31 to shift the power belt 11 from the fast to the loose pulley, and when this is done the machine is free to be raised into its inoperative position without removing the belt 55 from either of the pulleys over which it traverses.

The machine 1 is herein shown as having a supporting arm 44 pivoted thereto at 45 and adapted to rest on a supporting pin 46 60 extending from the base 3 thereby to support the machine in its elevated position. The supporting arm 44 is provided with a handle 47 by which it may be operated to withdraw it from the pin 46 when the machine is to be lowered. It is sometimes de-

sirable to swing the machine 1 farther back about its pivot than shown in Fig. 2, and if this is done the socket 20 will be withdrawn from the end of the strut 19.

I have provided herein a construction 70 which will maintain the strut 19 in proper position so that if the machine is swung far enough back to disengage it entirely from the strut, said strut will be maintained in a position to enter the sockets 20 again when the machine is brought back into the position shown in Fig. 2. The strut 19 is shown as passing up through a guiding slot 49 formed in the guide plate 50 secured to the bench or table 2, and the frame 10 is provided with a spring or resilient member 51 which engages the strut 19 and holds it against the end of the slot, thus maintaining the strut in position to enter the socket 20 when the machine is brought back into 75 the position shown in Fig. 2, after having been swung farther back about its pivot 4. The slot 49 is necessary to accommodate the lateral movement of the strut as the machine 1 moves from the position shown in Fig. 1 80 to that shown in Fig. 2.

A buttonhole sewing machine of the "Reece" type such as illustrated in United States Patents No. 488,028, and No. 494,280 is provided with an additional driving pulley 54 driven by a belt 55 separate from the transmission belt 6, this pulley 54 controlling the feed mechanism, while the pulley 5 drives the stitch-forming mechanism. Where my invention is used in connection with a 95 sewing machine of this type I will provide the countershaft 8 with another pulley 56 over which the belt 55 passes, said belt 55 being shown as a crossed belt to give the proper direction of rotation to the pulley 54. 100 The presence of two pulleys on the countershaft 8 is, however, essential only where the machine to be operated requires two separate transmission belts for its operation.

When the machine 1 is moved into its 105 in-operative position there may be more or less slackness in the transmission belt or belts, and to hold each transmission belt in proper position relative to its pulley so that it will automatically come back onto the pulley 115 again when the machine is moved into its operative position and the countershaft 8 has been carried into the position shown in Fig. 1, I propose to provide belt guides 69 which are associated with the pulleys on the 120 shaft 8. These belt guides insure that the belts will be brought back onto the pulleys when the countershaft 8 is lowered.

While I have illustrated the invention as 125 it might be applied in operating a button-hole sewing machine of the "Reece" type, yet I wish it distinctly understood that so far as the invention itself is concerned, it is capable of use for driving any machine which is constructed so as to be moved from 130

one position to another relative to the power element and, therefore, I do not wish to be limited in the use to which my invention is put, nor to the particular manner of mounting the countershaft 8 so that it can move with the machine.

It will be understood, of course, that the constructional details may be varied in many particulars depending on the character of 10 the machine with which the invention is used.

I claim:

1. In a power transmitter, the combination with a machine movable from its operative to its inoperative position, of a power element, a countershaft operatively connected to said machine and bodily movable toward and from the power element when the position of the machine is shifted, and means 20 to connect operatively said power element to the countershaft when the latter is in a position corresponding to the operative position of the machine.

2. In a power transmitter, the combination with a machine movable from its operative to its inoperative position, of a power element, a countershaft, a driving connection between said countershaft and machine, said countershaft being movable bodily relative to the power element to permit the machine to be shifted from one position to another without disconnecting the driving connection, and means to connect operatively said power element to said countershaft when the latter is in a position corresponding to the operative position of the machine.

3. In a power transmitter, the combination with a machine movable from its operative to its inoperative position, of a countershaft, a pulley fast thereon, a driving connection between said countershaft and machine, a power element comprising a belt, said countershaft being bodily movable relative to the power element to permit of the shifting of the machine from one position to another without disconnecting the driving connection, and means to connect said belt to or disconnect it from the fast pulley.

4. In a power transmitter, the combination with a machine movable from its operative to its inoperative position, of a countershaft, a pulley fast thereon, a driving connection between said machine and countershaft, said countershaft being bodily movable to permit the machine to be shifted from one position to another without disconnecting the driving connection, a driving belt, a loose pulley over which said belt normally operates, and means to shift the driving belt from the loose to the fast pulley when the countershaft is in a position corresponding to the operative position of the machine.

5. In a power transmitter, the combination with a machine movable from its operative to its inoperative position, of a countershaft, a transmission belt connected to said countershaft and machine, said countershaft being movable bodily to permit the machine to be shifted without disconnecting the transmission belt, a pulley fast on the countershaft, a loose pulley rotating about a fixed axis which is co-axial with the countershaft when it assumes a position corresponding to the operative position of the machine, a driving belt, and means to shift the driving belt from the loose to the fast pulley.

6. In a power transmitter, the combination with a machine movable from its operative to its inoperative position, of a countershaft, a transmission belt connected to said countershaft and machine, said countershaft being movable bodily to permit the machine to be shifted without disconnecting the transmission belt, a pulley fast on the countershaft, a loose pulley rotating about a fixed axis which is co-axial with the countershaft when it assumes a position corresponding to the operative position of the machine, a driving belt, a belt shifter for shifting the driving belt from one pulley to the other, a treadle, and connections between said treadle and belt shifter whereby movement of the treadle in one direction will shift the driving belt from the loose to the fast pulley, and movement in the other direction will shift the belt from the fast to the loose pulley.

7. In a power transmitter, the combination with a machine movable from its operative to its inoperative position, of a countershaft, a transmission belt connected to said countershaft and machine, said countershaft being movable bodily to permit the machine to be shifted without disconnecting the transmission belt, a pulley fast on the countershaft, a loose pulley rotating about a fixed axis which is co-axial with the countershaft when it assumes a position corresponding to the operative position of the machine, a driving belt, a belt shifter for shifting the driving belt from one pulley to the other, a treadle, connections between said treadle and belt shifter whereby movement of the treadle in one direction will shift the driving belt from the loose to the fast pulley and movement in the other direction will shift the belt from the fast to the loose pulley, and means yieldingly holding the belt shifter in either of its two positions.

In testimony whereof, I have signed my name to this specification.

JOHN KIEWICZ.
